UNITED STATES PATENT OFFICE

2,554,608

CLOTHES LIFTER

Edward P. Zimmerly, Chicago, Ill., assignor to
Estelle Anne Zimmerly, Chicago, Ill.

Application April 17, 1950, Serial No. 156,306

1 Claim. (Cl. 294—23.5.)

1

This invention relates to new and useful improvements in clothes lifting devices and the primary object of the present invention is to provide a stick for stirring, turning and lifting clothes in a convenient manner without the user having to handle the clothes or contact hot water in which the clothes are being soaked or washed.

Another very important object of the present invention is to provide a clothes lifter including a tip so constructed and shaped as to permit the tip to effectively grip a garment as the tip is rotated by a user.

A further object of the present invention is to provide a clothes lifting stick that is extremely strong and reliable in use to permit the lifting of relatively heavy and wet clothes and with the stick of sufficient length to provide the necessary leverage action.

A still further aim of the present invention is to provide a clothes lifter that is simple and practical in construction, easy to handle, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is an elevational view of the present clothes lifter;

Figure 2 is an enlarged end view of the present clothes lifter; and,

Figure 3 is a fragmentary longitudinal sectional view taken substantially on the plane of section line 3—3 of Figure 2.

Referring now to the drawings in detail, wherein for the purpose of illustration, there is disclosed a preferred embodiment of the present invention, the numeral 10 represents an elongated cylindrical shank or stick having a tapered end portion 12 that is integrally formed with a substantially semi-spherical knob or tip 14 whose radius is substantially equal to the radius of the stick 10.

The outer periphery of the tip 14 is provided with a plurality of circumferentially spaced grooves or channels 16 that are inclined relative to the longitudinal axis of the stick 10. The grooves 16 each include an inner end 18 and an outer end 20. The grooves diminish in depth and

width from their inner ends 18 to their outer ends 20 as this particular construction has proven to be most effective in gripping clothes.

The juncture J of the tip 14 with the end portion 12 is also quite effective in retaining clothes relative to the tip when the device is being used.

A suitable indicia bearing plate P is mounted on the stick 10 and preferably carries a name distinctive of the device.

10 In practical use of the lifter, the user grasping the stick 10 merely inserts the tip 14 into a garment and twists the stick so that the garment will be wrapped about the tip with portions of the garment received in the grooves 16. As the 15 stick is raised, the garment will remain on the stick until the stick is again twisted or rotated.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described as 25 preferred embodiment of the invention the same is susceptible to certain changes fully comprehended by the spirit of the invention as herein described and the scope of the appended claim.

Having described the invention, what is claimed 30 as new is:

A clothes lifting device comprising an elongated cylindrical stick having a tapered end, a substantially semi-spherical tip on said tapered end, said tip having a plurality of circumferentially spaced grooves therein, said grooves being inclined relative to the longitudinal axis of said stick and including inner and outer ends, the width of said grooves diminishing from the inner ends of said grooves toward the outer ends of 40 said grooves.

EDWARD P. ZIMMERLY.
